ATTORNEY

UNITED STATES PATENT OFFICE.

WILLIAM HERBERT GATES, OF NEW HAVEN, CONNECTICUT.

DIE HEAD.

Application filed June 10, 1921. Serial No. 476,387.

To all whom it may concern:

Be it known that I, WILLIAM HERBERT GATES, citizen of the United States, residing at New Haven, in the county of New Haven and State of Connecticut, have invented certain new and useful Improvements in Die Heads; and I do hereby declare the following to be a full, clear, and exact description of the invention, such as will enable others skilled in the art to which it appertains to make and use the same.

My invention relates to that class of thread cutting tools of the character known in the trade as "die heads," it being an improvement on the patent granted to me November 9, 1920, No. 1,358,074. In my former patent, the die actuating cam studs were anchored to a shell having a sliding movement over the die carrying head, and the means for holding the die head against rotation comprised a pin anchored in the shank of the die head with its projecting ends intended to have a free movement in elongated slots in the sides of the hollow shank of the overhanging bracket. This arrangement was located so close to the axis of the die head that the grip of the dies on the work would produce such a torsional strain on the pin that the dies would cramp and would not readily let go of the work when the end of the thread was reached.

In my present invention, the shell is anchored to the die carrying head, and has means provided thereon for freely embracing the sides of the overhanging bracket, and they are located so far from the axis of the die head as to eliminate all torsional strain. In the present invention, the die actuating cam studs are anchored in a follower having a longitudinal movement within the stationary shell.

Referring to the drawings wherein the same characters of reference indicate like parts throughout the several views;

Figure 1 represents a front elevation of the die head showing the threading dies closed;

Figure 2 is a front elevation of the die head showing the dies opened;

Figure 3 is a side elevation of the die head showing the position of the several operative members when the dies are closed, also broken view partly in section of the bracket shank;

Figure 4 is a side elevation of the die head showing the position of the several operative members when the dies are opened;

Figure 5 is a rear elevation of the die head on line 5—5 of Figure 3;

Figure 6 is a rear elevation of the cam stud follower plate, die head carrier and its shank;

Figure 7 is a detail inside elevation of the cam stud follower;

Figure 8 is an inside detail elevation of the die head carrier, locking bolt and springs;

Figure 9 is a detail side elevation of the die head carrier and locking bolt;

Figure 10 is a sectional view of several of the operative members of the die head, and broken view of the shank of the die head carrier on line 10—10 of Figure 1;

Figure 11 is a detail view of the cam lever;

Figure 12 are detailed views of a threading die and a cam stud;

Figure 13 is a broken reduced front elevation of the stationary shell, end view of the overhanging bracket, showing modified means for operatively connecting the shell to the bracket, and

Figure 14 is a reduced plan view of the die carrying head and shell, and broken view of the bracket, showing modified means for operatively connecting the head with the bracket.

1 represents the head carrying the radially operating dies 2. 3 is the usual front plate secured to the head by the screws 4. 90 The shell 5 is mounted on a part of the head 1 and is secured thereto by the screws 6. The upwardly extended projections 7 of the shell 5 freely embrace the sides of the overhanging arm 8 of the bracket 9 whose hollow shank 10 is adapted to be secured in a turret head or other like carrier, not shown, for actuating the die head to and from the work. The shank 11 of the head 1 has a free longitudinal movement in the hollow shank 10, and 100 12 is a relief spring located between the end of the shank 11 and the projection. The shank 11 carries the screw 14 on which the spring 15 is mounted to be compressed between the projection 13 and the screw head 16 on the forward travel of the die head for the purpose of returning said die head at the completion of its work, while the spring 12

will allow the die head to give back slightly and thus prevent the forcible contact of the dies with the work.

The follower 17 carries the studs 18 having the cams 19, Figure 12, on their forward ends registering with the cam grooves 20 formed in the sides of the dies 2. These studs are adapted to pass freely through the holes 21, Figure 8, of the die carrying head 1. The cam stud follower 17 has the large central opening 22, Figure 7, adapted to slide freely on the hub 23, Figures 10 and 11, of the cam lever 24. The trip lever 25, Figure 7, is journaled on the pin 26 located within the follower, and is adapted to engage with the notch 27, Figure 9, of the locking bolt 28 adjustably located in the head 1 by the screw 30. The trip lever 25 and its spring 31 was carried, in my former patent, by the sliding shell, but is now located, as before mentioned, in the follower.

32, Figure 6, is a plate adapted to be secured to the rear face of the follower 17, and its central opening 33 corresponds in diameter to the opening 22 of the follower. The opening 34, in the plate, is in alignment with the locking bolt 28, of the head 1, to give the proper end clearance to said bolt. The opening 34^a in follower, Figure 7, also affords a free passage for the bolt.

35, Figures 3, 4, and 8, are springs located in the holes 36 of the head 1, and 37, Figure 7, are corresponding holes through the follower 17 in which the opposite ends of the springs are located and rest against the inside face of the plate 32 when the die head is assembled.

The trip pin 38 is mounted in the arm 8 of the bracket, and is adjusted therein with respect to the trip lever 25 by the screw 39, and the nut 40 secures said pin in any of its adjusted positions.

The cam lever 24, Figure 5, is journaled on the shank 11 and is rotatably secured to the plate 32 by the screw 41 embraced by the curved slot 42. The bore of the cam lever, see also Figure 11, is provided with the cam grooves 43 adapted to engage with the projecting ends of the pin 44 located in the shank 11. The spring actuated stop pin 45, seen also in Figure 3, is adapted to be engaged by the shoulder 46 of the cam lever when the threading dies are closed, and by the opposite shoulder 47 when the dies are opened.

In detaching the cam lever from the plate 32, the screw 41 is removed, and the pin 45 depressed to allow the lever to ride over the pin in its reverse rotary movement until its internal cam grooves 43 have cleared the pin 44.

In operating the device, the assembled die head is advanced through the medium of a turret head, not shown, toward the work to be threaded, and during such advance, the

extension 24^a, of the cam lever 24, will engage with a stationary projection, not shown, in line with the forward movement of the die head and cause the cam lever to rotate toward the arm 8 of the bracket and into the position shown in Figures 1, 3, 5, and 10.

This rotative movement of the cam lever will advance the follower 17 with its cam studs 18 to close the dies in readiness to engage the work to be threaded. The thread cutting will continue a predetermined distance due to the position of the trip pin 38, when said pin will be engaged by the trip lever 25 and release said lever from its engagement with the notch 27 of the locking bolt, whereupon the springs 35 will force the follower back into its normal open position shown in Figure 4. This reverse movement of the follower will also cause a reverse movement of the cam lever 24 into its normal open position shown in Figures 2 and 4. As soon as the follower is released, the stored up tension in the spring 15 will instantly return the die head and its shank.

One of the principal features of the present construction, as before mentioned, is to shift the means for holding the die head against rotation to a point far enough from the axis of the head to eliminate the torsional strain thereon and thereby give the threading dies a free release from the work. The means shown in Figures 1 to 5 inclusive, comprise the projections 7 of the stationary shell, located on each side of the overhanging bracket. Other suitable means may be employed for this purpose which I hold myself at liberty to use. In Figure 13 the single member 48 is secured to the overhang 8 of the bracket 9 and projects into the elongated slot 49 of the shell 5. In Figure 14, the overhang 8, and the slot 50, in which the trip pin 38 is adjustably located, are extended over the die carrying head 1 so as to permit the projection 51 of the head to enter the slot and have a free longitudinal movement therein when said head is advanced or retracted.

Having thus described my invention what I claim is:—

1. In combination with a die head carrying radially operating dies, a shell embracing a part of the head and secured thereto, a follower operatively mounted in the shell carrying cam studs engaging the dies, a trip lever on the follower, a locking bolt carried by the head, an overhanging bracket, a cam lever for actuating the follower to close the dies and engage the trip lever with the locking bolt, means carried by the bracket to engage the trip lever and release the follower from the die head, and means carried by the shell adapted to engage the bracket to hold the head against rotation.

2. A die head carrying radially operating dies, a shell embracing the die head and im-

movably secured thereto, a follower operatively located within the shell and carrying die actuating cam studs, and external means engaging the shell to hold the head against 5 rotation.

3. A die head having a shank and carrying radially operating dies, a shell partially embracing the head and secured thereto, a follower operatively located within the shell 10 and carrying die actuating cam studs, a cam lever rotatably mounted on the shank in workable relation with the follower and having internal cam connection with the shank whereby the follower is actuated to close the 15 dies.

4. A die head carrying radially operating dies, a stationary shell, a follower operatively located within the shell and carrying die actuating cam studs, means for actuating 20 the follower to close the dies, means for lock-

ing the follower when the dies are closed, means for releasing the follower, and means substantially as shown to hold the head against rotation.

5. A die head carrying radially operating dies, a shell partially embracing the head and secured thereto, a follower operatively located within the overhanging portion of the shell and carrying die actuating cam studs, and means substantially as shown for 25 holding the die head against rotation.

6. A die head carrying radially operating dies, a stationary shell, a follower operatively located within the shell and carrying die actuating cam studs, and means externally located with respect to the head adapted 30 to hold said head against rotation.

35 In testimony whereof I affix my signature.

WILLIAM HERBERT GATES.
